US00D936117S

(12) **United States Design Patent** (10) **Patent No.:** **US D936,117 S**
Allen et al. (45) **Date of Patent:** **** Nov. 16, 2021**

(54) **STEP DRILL BIT**

(71) Applicant: **MILWAUKEE ELECTRIC TOOL CORPORATION**, Brookfield, WI (US)
(72) Inventors: **Douglas W. Allen**, Oconomowoc, WI (US); **Courtney D. McCool**, Menomonee Falls, WI (US); **Smith C. Theiler**, Plymouth, WI (US); **Richard Hohml, Jr.**, Racine, WI (US)

(73) Assignee: **Milwaukee Electric Tool Corporation**, Brookfield, WI (US)

(**) Term: **15 Years**

(21) Appl. No.: **29/713,951**

(22) Filed: **Nov. 20, 2019**

Related U.S. Application Data

(60) Continuation of application No. 16/250,175, filed on Jan. 17, 2019, now Pat. No. 10,695,845, which is a continuation of application No. 15/668,874, filed on Aug. 4, 2017, now Pat. No. 10,252,351, which is a division of application No. 14/297,777, filed on Jun. 6, 2014, now Pat. No. 9,731,358.

(57) **CLAIM**

We claim the ornamental design for a step drill bit, as shown and described.

DESCRIPTION

FIG. 1 is a left side elevation view of a step drill bit embodying our new design;

FIG. 2 is a front elevation view thereof; and,

FIG. 3 is an enlarged top plan view thereof.
Portions of the step drill bit shown in broken lines form no part of the claimed design.

1 Claim, 3 Drawing Sheets
